[57] CLAIM

The ornamental design for a design for a combined earmuffs and headband, as shown and described.

DESCRIPTION

FIG. 1 is a rear perspective view of a combined earmuffs and headband showing my new design;

FIG. 2 is a left side elevational view, the right side being a mirror image thereof;

FIG. 3 is a rear elevational view thereof;

FIG. 4 is a front elevational view thereof;

FIG. 5 is a top plan view thereof; and

FIG. 6 is a bottom plan view thereof.

The broken line showings represent conventional stitching.
